US00D782681S

(12) **United States Design Patent** (10) **Patent No.:** **US D782,681 S**
Cai et al. (45) **Date of Patent:** **** Mar. 28, 2017**

(54) **DISPOSABLE POLYMER-STRUCTURED FILTER**

(71) Applicants: **Jianjian Cai**, Dover, MA (US);
Xiaogao Liu, Dover, MA (US)

(72) Inventors: **Jianjian Cai**, Dover, MA (US);
Xiaogao Liu, Dover, MA (US)

(73) Assignee: **CHEMRUS INC.**, Dover, MA (US)

(**) Term: **14 Years**

(21) Appl. No.: **29/511,787**

(22) Filed: **Dec. 13, 2014**
